(57) **CLAIM**

The ornamental design for a ceiling mounted cardiac scanner, as shown and described herein.

DESCRIPTION

FIG. 1 is a rear perspective view of a ceiling mounted cardiac scanner in accordance with the present invention.

FIG. 2 is a front perspective view of the ceiling mounted cardiac scanner of FIG. 1; and,

FIG. 3 is a front perspective view of the ceiling mounted cardiac scanner of FIG. 1.

The broken lines in the drawing views are included for the purpose of illustrating portions of the ceiling mounted cardiac scanner that form no part of the claimed design.

1 Claim, 3 Drawing Sheets

FIG. 1

FIG. 2

FIG. 3
